UNITED STATES PATENT OFFICE.

VICTOR E. RANDALL, OF BATTLE CREEK, MICHIGAN, ASSIGNOR OF ONE-HALF TO
BENJAMIN GWATKIN, OF BATTLE CREEK, MICHIGAN.

RAILWAY-TIE.

1,306,437.

Specification of Letters Patent. Patented June 10, 1919.

Application filed September 29, 1917. Serial No. 194,019.

To all whom it may concern:

Be it known that I, VICTOR E. RANDALL, a citizen of the United States, residing at Battle Creek, in the county of Calhoun and 5 State of Michigan, have invented certain new and useful Improvements in Railway-Ties, of which the following is a specification.

This invention relates to railway ties, and 10 more particularly applies to that class of ties in which the superstructure or body is composed of concrete or equivalent material within which a framework or stiffening bond of metal is provided, the same being formed 15 into requisite shape and of suitable dimensions for the purpose.

The present invention contemplates the adoption of two substantially equal proportioned sections carrying longitudinally-mov- 20 able metallic shim holders, the same being fitted with resilient shims for the reception of the T-rails, each of the respective tie sections being provided with longitudinally embedded metallic bonds having protruding 25 eyelets adapted to engage the hooked ends of connective links to secure the sections intact, clamps for securing the rails that will permit a variation of adjustment of said rails on the respective tie sections, and an 30 improved method for securing the clamps to the tie; and among other objects of the invention is to provide a tie of the class whereby an equal distribution of the weight of the rolling stock will be transmitted to 35 the respective tie sections; whereby the sections comprising a tie may be connected at either end indiscriminately; whereby by the provision of the links connecting the tie sections, a flexible union will be afforded and 40 breakage of the tie through heaving of the ground from freezing will be prevented; whereby a number of tie sections may be connected as may be expedient in laying several lines of rails through yards, switches, 45 etc.; whereby longitudinal displacement or creeping of the tie will be prevented by the tamping of ballast between the tie sections; whereby the rail-clamping mechanism will permit the rails to be fastened to the tie 50 other than at predetermined places; whereby resiliency of the rolling stock will be provided through an arrangement of shim holders and resilient shims fitted therein for seating the rails, and whereby the ties will

lay to better advantage than wood or me- 55 tallic ties, be less expensive than metallic ties, supporting capacity considered, and not affected by deterioration through the effects of climate or soil, economical to build, and enduring. Other objects and advantages 60 will hereinafter appear in the following specification and be particularly set forth in the appended claims forming a part thereof.

In the drawings forming part of this specification, Figure 1 is a side elevation of 65 my improved tie with rails attached.

Fig. 2 is a plan view of the same.

Fig. 3 is a plan view of one of the tie sec- 70 tions.

Fig. 4 is a longitudinal side elevation of a tie section bisecting the clamping plug hole.

Fig. 5 is a plan view of a tie section in 75 modification.

Fig. 6 is a broken longitudinal side eleva- 75 tion of a tie section bisecting a clamping plug and its clamp.

Fig. 7 is a perspective view of a clamp- 80 ing plug.

Fig. 8 is a perspective view of a metallic 80 shim holder.

Like marks of reference refer to corre- 85 sponding parts throughout the different views, in which "A—A" represents the tie sections and "B—B" the T-rails.

The tie sections are formed of concrete or 85 equivalent material, and a preferred form is to make them in cross-section parallelo- 90 grams somewhat wider in transverse section.

In Figs. 1, 2, 3, 4 and 6 each tie section is formed with two longitudinally-disposed metallic bonds 1, 1, provided with eyelets 2 at either end thereof which protrude from the tie sections. These bonds are arranged parallel and are located near either edge of the tie section centrally thereof and per- 95 form a four-fold purpose, viz., trusses to prevent the tie sections from breaking, eyelets to permit the sections to be hauled from place to place, hinges to give flexibility be- 100 tween the tie sections, and brace bearings within which connective links 3 will prevent one section from side movement with respect to the other. By preference the links cross one another X-fashion, as shown in Fig. 2, and the curved terminals of the respective 105 links are fitted with washers 4 and cotter pins 5, one link being fitted below, the other above the eyelets.

In the modified form shown in Fig. 5, the bond 1' is formed U-shaped, the eyelets 2 thereof protruding from one end of the tie section, only.

- 5 To afford a more stable structure, I prefer to connect the bonds of the tie section near either end by means of metallic tie strips or strands 6, and where the bond is of U-shape construction, to connect the same 10 near the free extremities thereof in like manner, as shown in Fig. 5.

Molded within each tie section, and preferably in diagonal alinement, are metallic guide-rests 7. These guides have downwardly-extending limbs embedded within the tie section while their exposed surfaces protrude slightly above the tie sections and form guides or holders over which the split feet of the rail clamps 8 may rest. In alinement with the guides aforesaid and toward the center of a tie section, the clamping plug-holes 9 are formed. These holes may extend through the tie or not, as expedient, and molded within the tie section and protruding axially within each hole a metallic fin 10 is provided. Fitted within the holes 9 are resilient plugs 11. These plugs by preference are of wood suitably treated to retard decay, or made of compact paper 30 treated with asphaltum for the same purpose. That a plug may be readily fitted within a hole, a longitudinal kerf or slip 12 is made, which strides a fin 10 and prevents said plug turning when the clamping bolt 35 is turned to hold a clamp, as will be herein-after set forth.

Fitted upon a tie section between the holes 9, 9, a shim holder 13 (see Fig. 8) is placed. This shim holder preferably is of 40 sheet metal having its ends 14 turned down to form guides to keep the same from cross displacement on the tie, a portion of its center being cut away and a part of the longitudinal side portions turned up at right 45 angles to the base to form sides 15, between which a wooden or other resilient shim or rail seat 16 may be placed, the shim itself resting directly upon the tie section. Seated upon the shim 16 are the T-rails B, and upon 50 either side of a rail clamps 8 are fitted. These clamps are T-shaped, the foot of the clamp being curved to rest upon the tie section, the stem of a clamp having a longitudinal slot 18 through which a clamping bolt or 55 screw 19 may pass. That the foot of a clamp may be held from side thrust, a slot, not shown, is formed in the foot thereof, through which a guide 7 of the tie fits, and that a clamp may be held from longitudinal 60 thrust, the top of each clamp is corrugated crosswise and a correspondingly corrugated washer or cap 20 is seated thereon, the cap by preference having depending sides which 65 stride the clamp and tend to hold the same more firmly in position.

Passing through a cap and its clamp, a lag screw 19 is placed, its point entering a hole within a plug 11 into which it is screwed. By providing a hole in a plug smaller than the lag screw, the plug will expand sufficiently to prevent it from displacement when the lag screw is fitted therein.

In the drawings I have shown the shim holder 13 with sides somewhat taller than the depth of the shim 16, although this is not essential in every case; a holder of the character described should have portions of its up-turned sides slotted, as α , α , to receive the free ends of the clamp, a provision whereby a clamp may rest firmly upon the rail flange and form at the same time a seat for the clamp preventing it from side thrust.

It will be obvious by the provision of the slotted clamps as set forth that a rail may be shunted sidewise, together with its bearing, should occasion arise in lining up the rails without affecting the tie itself, by releasing the lag screws and moving the clamps to accommodate a rail.

From the foregoing description taken in connection with the drawing a more extended explanation of the working and advantages of my invention is believed will not be necessary.

Having described my invention, what I claim, therefore, as new and desire to secure by Letters Patent, is:

1. A railway tie, the combination of two rail bearing sections, each section thereof having a metallic rod provided with an eyelet at either end adapted to protrude from the ends of said section near either edge transverse thereof, and detachable obliquely disposed links adapted to engage the eyelets of respective sections.

2. A railway tie, the combination of two rail bearing sections, each section thereof having two centrally disposed parallel-arranged rods provided with eyelets at either end thereof adapted to protrude from the ends of said sections, and obliquely-disposed links adapted to engage the eyelets of the adjacent sections, and means to retain said links in position.

3. A railway tie, the combination of two rail bearing sections, each section thereof having two centrally-disposed longitudinally-arranged rods provided with eyelets in either end thereof extending from the ends of said section, tie strips or bands connecting said rods intermediate said eyelets within said tie section, and obliquely-disposed links having curved ends adapted to engage the eyelets of the adjacent sections, and means to detachably hold said links in position.

4. A railway tie, the combination of two rail-bearing sections, each section thereof having two centrally-disposed parallel ar-

ranged rods provided with horizontally-disposed eyelets at either end thereof adapted to protrude from the ends of said sections, and obliquely-disposed links having curved extremities engaging through said eyelets, washers fitted over said curved extremities and cotter pins fitted through said curved

extremities between the ends thereof and said washers, as and for the purpose set forth.

VICTOR E. RANDALL.
